UNITED STATES PATENT OFFICE

HUBERT McL. ARMISTEAD, OF SAN FRANCISCO, CALIFORNIA, ASSIGNOR TO THE CONDOR COMPANY, OF SAN FRANCISCO, CALIFORNIA, A CORPORATION OF NEVADA

DOORCHECK

Application filed February 24, 1930. Serial No. 443,775.

The present invention relates to that class of door checks in which the restricted circulation of a confined fluid serves as a yielding resistance to the closing of a door, and constitutes an improvement on the devices disclosed in United States Patents Nos. 1,704,217 and 1,736,175.

My invention is preferably embodied in a yielding resistance member comprising a cylinder, a reciprocable piston, and a confined circulating body of liquid, said resistance member being positioned in the door frame or casing, and operated by a separate presser member secured to the door and adapted to engage said piston upon the closing of the door. Obviously, however, the positions of the two members may be reversed. The cylinder and piston assembly is so constructed that it can be mortised into the door frame or the rear stile of the door, as the case may be, and thus concealed from view.

The object of my invention in general is to provide a simple and effective device for checking the closing of a door without otherwise affecting its movement. More particularly my object is to provide such a device which will retain its checking fluid without leakage for a long period of time, and which can be easily adjusted to provide a smooth and gradually increasing resistance to the closing of the door with a sufficient relief of such resistance at the end of the closing movement to insure the proper latching of the door.

Other objects and advantages of the invention will become apparent from the following description which should be read with the understanding that the construction, form and arrangement of the several parts may be varied within the limits of the claims hereto appended without departing from the spirit of the invention as set forth in said claims.

With this in view, the preferred embodiment of my invention will now be described fully with reference to the accompanying drawings wherein

Fig. 1 is a vertical central section of the device, the presser member being omitted.

Fig. 2 is a horizontal section on the line

2—2 of Fig. 1 showing in addition the presser member.

Figs. 3, 4, 5 and 6 are transverse sections taken on the correspondingly numbered lines of Fig. 2.

Fig. 7 is a sectional detail of the initial relief port taken on the line 7—7 of Fig. 3.

In the drawings, the reference numeral 1 designates a body or shell in which is formed a cylinder 2. A piston 3, operable in said cylinder, has a stem 4 which extends forwardly and projects through the forward or outer end of the shell 1. In order to prevent leakage around the stem 4, I provide suitable packing 5 interposed between a metallic ring 6 and a guide sleeve 7, the latter having considerable length and closely surrounding the stem 4. A threaded ring or annular nut 8 retains the guide sleeve 7 in position and compresses the packing 5 between the inner end of said sleeve and the ring 6. A shoulder 9 formed in the bore of the cylinder 2 provides an abutment for said ring 6.

The shell 1 is adapted to be mortised into either the door or its frame, as shown in Fig. 2, in which 10 indicates, for example, a portion of the door frame, and 11 is a portion of the door, the hinged relation of the two being indicated by the dotted lines 12. The piston stem 4 normally projects as shown, and is adapted to be engaged and forced inwardly when the door is closed by a presser member 13 secured to the rear edge of said door. The presser member is preferably formed as shown with an offset end 14, and a recess 15 in one side, this shape permitting the maximum length of stroke for the stem 4 and piston 3. It will be apparent, although such position is not shown in the drawings, that when the door is closed, the entire presser member 13 is housed within the sleeve 7, the stem 4 and piston 3 receding sufficiently to render this possible. By this construction, the device is entirely concealed when the door is closed, and its only projecting parts when the door is open are the stem 4 and the presser member 13.

A spring 16, Fig. 1, forces the piston 3 outwardly when the door is opened. In order to provide the greatest possible length

for said spring, the stem 4 is hollow, and one end portion of the spring rests within it. The other end of said spring surrounds a fixed stud 17, and is guided thereby to prevent 5 buckling.

A reservoir 18 is formed in the shell 1, preferably above and in alignment with the cylinder 2. A screw plug 19 permanently 10 closes the outer end of said reservoir. At the inner or rear end of the shell, a passage 20 connects the cylinder 2 with the reservoir 18. A check valve 21, mounted in the base of the stud 17, closes the passage 20 to fluid flow from the cylinder 3 to the reservoir 18, but 15 permits free flow in the opposite direction.

The forward end of the cylinder 2 is connected with the reservoir 18 by a free passage 22. The rear end of the cylinder is provided with a port 23 having a connection 24 with 20 the passage 20. An adjustable needle valve 25 controls the flow of fluid through said passage 24. The valve 25 comprises an elongated stem extending inwardly and operable from the outer end of the shell. It extends through 25 the free passage 22, and is preferably threaded into the body of the shell 1 on both sides of said passage, as shown at 26. By this construction, any fluid which leaks along the threads of the stem returns to the cylinder 30 through the passage 22, and is not forced out to the outer end of the stem.

The needle valve 25 is the principal adjusting or controlling valve of the device. When the piston 3 is moved inwardly, i. e. 35 toward the right in Fig. 1, by the closing of the door, the fluid, which is assumed to fill the cylinder 2 and the greater part of the reservoir 18, is compressed between the piston and the check valve 21. An outlet for 40 said fluid is provided by the port 23 and valve controlled passage 24. Therefore, by adjusting the valve 25, the amount of resistance offered to the closing of the door by the trapped fluid in the cylinder 2 can be regulated.

I prefer to use a liquid for the checking fluid. The checking action therefore begins 50 immediately upon the inward movement of the piston 3, or in other words, as soon as the presser member 13 strikes the end of the stem 4, upon the closing of the door. In order to provide a gradual increase of the checking effect, and to prevent undue strain on the door and its hinges by a too sudden application 55 of said checking effect, I provide an initial relief port 27 in the wall of the cylinder 2, at a point about midway between its ends. A passage 28 connects said port with the passage 20, and a needle valve 29, similar 60 in construction to the valve 25, controls said passage. Therefore, when the piston begins to move inwardly, the liquid can flow through both ports 23 and 27 until the latter is covered by the piston. The initial checking action 65 is therefore relieved and can be regulated

by adjusting the valve 29. I also provide a tapering groove 30, Figs. 3 and 7, in the wall of the cylinder extending rearwardly from the port 27 for a short distance. This groove 30 has its deepest portion at said port, and gradually decreases in depth until it disappears. The effect of said groove is a gradual closing of the port 27 by the piston 3, so that the increase in checking action between the initial and subsequent periods of 70 piston movement is gradual rather than sudden. 75

The cylinder 2 has a third port 31, Figs. 2 and 4, some distance forward of the port 23 and connected therewith by a passage 32. A needle valve 33, similar to the valves 25 and 29, controls said passage 32. The distance between the ports 31 and 23 is slightly greater than the length of the piston 3, so that when the piston has cleared the port 31, the liquid can flow through the port 23, the passage 32 and the port 31 into the forward end of the cylinder, thus relieving the checking action at the end of the stroke of the piston. This relief, which is controlled by the adjustable 80 needle valve 33, is intended to allow the door sufficient freedom of action at the end of its closing movement to insure its latching.

The reservoir 18 is intended to contain a supply of liquid in order to insure that the cylinder 2 will be full at all times. The reservoir also forms a conduit through which the liquid flows in passing from one end to the other of the cylinder 2. At the upper forward end of said reservoir there is provided an extension chamber 34 through which the liquid may be introduced. The shell 1 is preferably secured by screws 35 and 36 to a face plate 37 which may, if desired, be one of the plates of the door hinge. An aperture 38 is provided in said plate to permit access to the adjustable needle valves 25, 29 and 33. The upper screw 36 forms a closing plug for the liquid supply chamber 34, and is provided with an aperture 39 forming a vent. In filling the device with liquid, the screw 36 is removed and the spout of a suitable container, such as an oil squirt can, is inserted into the filling chamber 34. A vent 40 is provided in the wall dividing said chamber from the reservoir in order to permit escape of air during the filling operation. The spout of the filling can is inserted beyond said vent 40 so that the air may escape through said vent and around said spout without obstructing the downward flow of the liquid from the end of said spout. 100

It is to be noted that there is practically no chance for leakage of the checking fluid. The rear end of the cylinder 2, in which the fluid is placed under pressure, has no outlets other than the ports and passages leading to the reservoir 18, nor are there any seams or joints in the rear end of said cylinder. On account of the free passage 22 and the 110 120 125 130

vent 39, there can be no appreciable pressure in the forward end of the cylinder, so that the packing 5 can easily prevent leakage around the piston stem 4. The vent 39, entering the chamber 34 at the top of the reservoir, is always well above the level of the liquid therein. If, due to overfilling of the reservoir, there occurs any leakage of the liquid through the vent 39, it will at once appear 10 on the face of the device, and will give warning of its occurrence. By extending the threaded portions of the needle valves 25, 29 and 33 through the free port 22, any leakage of liquid around said valves is prevented 15 from reaching the face of the device.

The plurality of valve controlled relief ports in the cylinder enables the device to be adjusted easily to provide smooth and positive operation. In adjusting the device, the 20 needle valve 25 is first adjusted to provide the desired normal closing speed of the door. The valve 29 is then adjusted to relieve the initial checking action so that the normal action is attained gradually and smoothly. 25 The valve 33 is then adjusted to provide the necessary amount of relief at the end of the movement to insure proper and complete closing and latching of the door.

I claim:

30 1. A door check comprising a shell of greater height than width and adapted for insertion in a door frame, said shell having a cylinder, a reservoir in parallel superposed relation thereto, an unrestricted passage connecting the forward end portion of said cylinder with said reservoir, and a plurality of ports connecting other portions of said cylinder with said reservoir; needle valves for controlling said ports, said valves being 35 provided with stems extending from the front of said shell rearwardly between said cylinder and said reservoir and through said passage, and having threaded engagement with said shell on both sides of said passage; 40 and a piston operable in said cylinder to circulate fluid through said ports, passage, and reservoir.

2. A door check comprising a shell of greater height than width and adapted for 45 insertion in a door frame, said shell having a cylinder and a reservoir in parallel superposed relation and passages connecting the front and rear end portions of said cylinder with said reservoir, said cylinder having a 50 plurality of ports progressively spaced from its rear end, two of said ports connecting directly with said rear passage and thence with said reservoir, and a third port connecting with one of the first ports; adjustable valves 55 controlling said port connections; a check valve between said cylinder and said rear passage; and a piston operable in said cylinder to circulate fluid through said ports, passages and reservoir.

60 65 3. In a fluid resistance door check adapted

for insertion in a door frame, a shell having an interior fluid containing compartment and a filling chamber communicating therewith; a face plate; and screws extending through said face plate for securing said shell thereto, one of said screws extending into said filling chamber and forming a removable closure therefor. 70

4. In a fluid resistance door check adapted for insertion in a door frame, a shell having an interior fluid containing compartment and a filling chamber communicating therewith; a face plate; and screws extending through said face plate for securing said shell thereto, one of said screws having a vent 75 aperture formed through it, and said apertured screw extending into said filling chamber to form a vented removable closure therefor.

In testimony whereof I have signed my 80 name to this specification.

HUBERT McL. ARMISTEAD.
